CIGAR LIGHTER

Filed Oct. 16, 1929

Inventor:
John Sinko,

By Fisher, Clapp, Soans & Pond, Atty's.

UNITED STATES PATENT OFFICE

JOHN SINKO, OF CHICAGO, ILLINOIS

CIGAR LIGHTER

Application filed October 16, 1929. Serial No. 399,929.

This invention relates to electric cigar lighters of the class used on automobiles, and has reference more particularly to a type commonly known as "wireless" lighters, which are characterized by the provision of a socket member mounted on the dash or other part of the car body and carrying contact terminals wired to the battery, and a plug member comprising a hand piece carrying an igniter element and a cooperating contact terminal, the plug member being moved in the socket member to close the circuit through said contact terminals and held in such position until the igniter element has become heated to incandescence, and then removed from the socket member for use.

My present invention is in the nature of an improvement upon a cigar lighter forming the subject matter of an application heretofore filed by me on the 31st day of October, 1928, Serial No. 316,164, and among its objects are, to simplify the construction of the aforesaid application, and to provide a construction wherein the plug member will be more securely held in the socket member against accidental dislodgement.

The present invention is illustrated, as to its preferred construction, in the accompanying drawing, in which—

Fig. 1 is an axial sectional view of the lighter and its supporting bracket.

Fig. 2 is a front elevation of the same.

Fig. 3 is a horizontal axial section through the front limb of the supporting bracket and the mounting means for the socket terminal.

Fig. 4 is a group view showing in front and rear perspective a spring-supported element of the socket member which receives and clamps the removable plug member.

Fig. 5 is a front elevation of the front limb of the supporting bracket.

Fig. 6 is an enlarged sectional detail taken on the line 6—6 of Fig. 5, and showing a portion of the terminal supporting disc engaged therewith.

Referring to the drawing, 10 designates as a whole, a U-shaped attaching bracket, the forward upstanding limb 10^a of which carries the lighter, and the rear upstanding limb 10^b of which carries a binding screw 11 by

which the bracket may be clamped on the lower edge of an instrument board. The lower horizontal limb of the bracket and the lower portion of the forward limb 10^a are preferably slotted as shown, to facilitate the passage of a circuit wire.

Mounted on the circular rim of the front bracket limb 10^a is a circular metal shell 12 formed with an inwardly curled front marginal stop flange 13. Within the shell 12 and abutting at its outer end against the flange 13 is a cup-shaped member 14, shown in isolated detail in Fig. 4, formed on its front and with an outwardly directed marginal flange 15 that normally abuts against the marginal stop flange 13 of the shell 12. By reference to Fig. 4 it will be observed that the circular wall and marginal flange of the cup-shaped member 14 are formed with spaced transverse slits or kerfs 14', four of which, spaced 90° apart, are herein shown; but a greater or less number may be employed. The rear ends of the kerfs 14' are also preferably extended for a slight distance into the bottom wall of the cup-shaped member. The purpose of these slits or kerfs is to give to the circular wall a limited capacity for contracting and expanding. To increase the contracting tendency of the circular wall I preferably employ a circular spring wire 16 that hugs the wall just under the flange 15, this spring tending to draw inwardly the sections of the wall formed between the slits or kerfs 14'. The bottom wall of the member 14 is formed with an inwardly pressed low circular boss 14^a formed with a central opening 14^b for a purpose hereinafter described.

Describing next the contact terminal of the socket member and its supporting or mounting means, and referring to Figs. 3, 5 and 6, the opposite sides of the circular forward limb 10^a of the supporting bracket are formed with outwardly pressed arcuate lugs 17, which are centrally apertured as shown at 18. Lying against the outer faces of the lugs 17 is a thin disc 19 of steel or other elastic sheet metal, which is centrally apertured to receive a terminal stud 20, that is formed on its inner end with a rounded head 20'. The stud 20 is insulated from the disc 19 by

fiber washers 21 and 22, the former of which has a reduced inner portion 21' filling the aperture in the disc 19 through which the stud 20 extends. A wire lead 23 from the battery is wound around the other end portion of the stud 20 being clamped between the fiber washer 22 and a brass washer 24 that is locked on the stud by an outwardly swaged lip 25 on the end of the latter. By reference to Figs. 3 and 6, it will be observed that the elastic disc 19 is formed at diametrically opposite points thereof with indented lugs 26 on the rear side thereof that fit into the holes 18 of the bracket bosses 17. These lugs 26 lock the disc 19 against turning movement and also against edgewise displacement, thus accurately centering the contact stud 20; and the elasticity of the disc 19 permits the contact stud 20 to yield slightly rearwardly when the cooperating plug member is pushed inwardly to close the circuit, as hereinafter more fully described.

Encircling the cup-shaped member 14 and abutting its outer end against the flange 15 and its inner end against the disc 19 is a coil spring 27, which normally urges the cup-shaped member 14 outwardly.

The parts thus far described are all permanently mounted on and carried by the bracket 10.

The removable plug element of the lighter is substantially identical with the corresponding element disclosed in my former application above identified but may be briefly described as follows.

28 designates a hand piece of bakelite, hard rubber, or other like material having the general form of a telephone transmitter mouth piece and formed with an internal annular rib 29. Locked on the rib 29 is the outer end of another metal cup-shaped member 30, the latter being formed at its outer end with an enlargement 30' tightly fitting the circular wall of the rib 29, and said enlargement having an annular flange 30^a seated on the outer side of the rib 29. To center and lock the member 30 in place, an annular metal washer 31 is driven over the body of the member 30 into engagement with the inner side of the rib 29. The inner or bottom wall of the cup-shaped member 30 has a laterally offset portion 32 formed with a central aperture 33 through which, and out of contact with the edge of aperture 33, extends a tapped contact stud 34 supported by a fiber washer 35 seated in the inset 32. Stud 34 has a kerf 34' in its head for application and adjustment by a screw driver. Seated in the open front end of the member 30 is a shallow igniter carrier 36 formed with a marginal flange 36' on its outer end overlapping the flange 30^a. The igniter carrier 36 has a central hole 37 through which extends with clearance a screw 38 supported by fiber washers 39 and 40, the former of which has a

reduced inner portion 39' filling the hole 37 in the igniter carrier 36. The fiber washers 39 and 40 are clamped on the carrier 36 by a brass washer 41 and nut 42. The inner end of the screw 38 enters the tapped contact 34. The head of screw 38 is slotted to receive the inner end of the spiral igniter element 43, the outer end of the latter being electrically connected to the rim of the carrier 36, which latter lies in contact with the outer end of the member 30.

In operation, the spring 27 normally maintains the contacts 34 and 20 separated. To heat the ignition coil 43, the hand piece 28 is pressed inwardly, compressing spring 27, and closing the circuit between contacts 20 and 34, the circuit being grounded on brace 10 through parts 36, 30, 14^a, 14, springs 16 and 27, and disc 19; it being noted that when the hand piece is fully entered in the socket member, the ground circuit is closed by contact of the inner end of the member 30 with the boss 14^a. The hand piece is held pressed in until the coil is incandescent, when it is pulled out of the socket and used. When replaced, spring 27 separates the contacts 20 and 34 as soon as the hand is removed from the hand piece 28.

The disc 19 being flexible, when the hand piece is pushed inwardly, the contact 20 may yield slightly rearwardly, thus insuring a spring-pressed bearing thereof on the head of the contact 34, making a more reliable and perfect contact than where the rear terminal stud is rigidly held.

The shank of the hand piece 28 is of such a diameter as to have a snug sliding fit in the cup-shaped member 14, and as the plug is pushed inwardly the circumferential wall sections of the member 14 expand slightly and hug the shank of the hand piece by virtue of their own resiliency, aided by the contracting force of the spring 16, where the latter is used. This construction provides a very secure grip of the socket member on the plug member which effectively prevents accidental dislodgment of the plug member under the jolting movements of the car. It will also be noted that the described construction provides an annular air space of substantial size between the metal cylinder 30 on which the igniter is mounted and that portion of the hand piece 28 surrounding the same, which serves as a heat insulation for the hand piece. In my present construction this insulation space is considerably enlarged over the corresponding insulation space disclosed in my pending application above identified.

I claim:

1. In a wireless cigar lighter, a socket member including an outer shell formed with an internal stop flange on its forward end, and a spring metal cup-shaped member within said shell, the bottom wall of said

cup-shaped member being apertured and its circumferential wall being expansible to telescopically receive and grip a cooperating plug member inserted therein, a spring in 5 said shell urging said cup-shaped member outwardly against said flange, and a circuit contact terminal disposed in rear of said cup-shaped member adapted to engage through the aperture of the latter with a 10 contact terminal on the plug member when the latter is pushed inwardly compressing said spring.

2. In a wireless cigar lighter, a socket member including an outer shell formed 15 with an internal stop flange on its forward end, a spring metal cup-shaped member within said shell having a centrally apertured bottom wall and an external annular flange adapted to contact with said stop 20 flange, the circumferential wall and annular flange of said cup-shaped member being longitudinally split to telescopically receive and grip a cooperating plug member inserted therein, a spring embracing and 25 compressing said circumferential wall, a coil spring in said shell encircling said cup-shaped member and urging the latter outwardly against said stop flange, and a circuit contact terminal disposed in rear of 30 said cup-shaped member adapted to engage through the apertured bottom wall of the latter with a contact terminal on the plug member when the latter is pushed inwardly compressing said last-named spring.

3. In a wireless cigar lighter, a socket member including an outer shell formed 35 with an internal stop flange on its forward end, and a spring metal cup-shaped member within said shell, having on its forward end 40 an external annular flange adapted to contact with said stop flange, and its bottom wall being apertured, the circumferential wall and annular flange of said cup-shaped member being longitudinally split to telescopically 45 receive and grip a cooperating plug member inserted therein, a coil spring in said shell encircling said cup-shaped member and urging the latter outwardly against said stop flange, and a circuit contact terminal 50 disposed in rear of said cup-shaped member adapted to engage through the aperture of the latter with a contact terminal on the plug member when the latter is pushed inwardly compressing said spring.

4. In a wireless cigar lighter, the combination with a supporting bracket plate, of a socket member including an outer shell mounted on said bracket plate and formed 55 with an internal stop flange on its forward end, a spring metal cup-shaped member within said shell, the bottom wall of said cup-shaped member being apertured and its circumferential wall being longitudinally split to telescopically receive and grip a cooperating 60 plug member inserted therein, a terminal

supporting plate mounted on the outer face of said bracket plate, a coil spring in said shell footed on said terminal supporting plate and urging said cup-shaped member outwardly against said stop flange, and a circuit contact terminal mounted on said terminal supporting plate in rear of said cup-shaped member adapted to engage through the aperture of the latter with a contact terminal on the plug member when the latter is pushed inwardly compressing said spring.

5. In a wireless cigar lighter, the combination with a supporting bracket plate, of a socket member including an outer shell mounted at its outer end on said bracket plate and formed with an internal stop flange on its forward end, a spring metal cup-shaped member within said shell, the bottom wall of said cup-shaped member being formed with a centrally apertured outwardly extending boss and its open end formed with a circumferential flange adapted to abut against said stop flange, the circumferential wall and flange of said cup-shaped member being longitudinally split, a terminal supporting disc mounted on the outer face of said bracket plate within said shell, cooperating locking means on said bracket plate and disc acting to center the latter on said bracket plate, a coil spring in said shell footed on said disc and urging said cup-shaped member outwardly against said stop flange, a circuit contact terminal centrally mounted on said disc, and a removable plug member comprising a hand piece insertable in said cup-shaped member and gripped by the longitudinally split wall of the latter, a rearwardly extending metal tubular member mounted in said hand piece at its inner end abutting against said boss when said hand piece is inserted, an ignition element mounted in said hand piece, said ignition element being electrically connected at one end to said tubular member, a second contact terminal mounted in and insulated from said boss and normally separated from said first-named contact terminal by said spring, and an electrode connecting the other end of said ignition element with said second contact terminal.

JOHN SINKO.
